[57] CLAIM

The ornamental design for a universal stroller shield, as shown and described.

DESCRIPTION

FIG. 1 is a perspective view of a universal stroller shield showing my new design with the universal stroller shield mounted on a stroller shown in dashed lines, the stroller not being part of the present invention;

FIG. 2 is a top plan view of the universal stroller shield of FIG. 1;

FIG. 3 is a right side elevational view of FIG. 2, the left side being a mirror image thereof;

FIG. 4 is a front elevational view of FIG. 2;

FIG. 5 is a bottom plan view of FIG. 2;

FIG. 6 is a perspective view of a universal stroller shield showing a modified design with the universal stroller shield mounted on a stroller shown in dashed lines, the stroller not forming a part of the present invention;

FIG. 7 is a top plan view of the universal stroller shield of FIG. 6;

FIG. 8 is a right side elevational view of FIG. 7, the left side being a mirror image thereof;

FIG. 9 is a front elevational view of FIG. 7; and,

FIG. 10 is a bottom plan view of FIG. 7.
